UNITED STATES PATENT OFFICE.

ERNST MUNTWYLER, OF LUCERNE, SWITZERLAND.

ELECTRIC FLATIRON.

1,402,245.

Specification of Letters Patent.

Patented Jan. 3, 1922.

Application filed September 13, 1920. Serial No. 410,004.

To all whom it may concern:

Be it known that I, ERNST MUNTWYLER, a citizen of the Republic of Switzerland, and resident of Lucerne, in the Canton of 5 Lucerne, Switzerland, have invented new and useful Improvements in Electric Flat-irons, of which the following is a specification.

A great disadvantage, especially when 10 ironing damp fabrics, consists in that the lower part of flatirons is quickly cooled off while the upper part of the iron remains warm without, however, being adapted to be utilized.

15 This invention has for its object to obviate such drawback the upper and lower parts of the flatiron being equally adapted for ironing purposes. In the accompanying drawing:—

20 Fig. 1 shows a side elevation, partly in section, of the electric flatiron; Fig. 2 shows an end elevation, and Fig. 3 a plan, partly in section, of Fig. 1, while Fig. 4 shows a section through line A—B in Fig. 3.

25 1 designates the body of the flatiron in the hollow interior of which the electric heating device is mounted in the known manner. Also mounted in the hollow chamber and secured by a screw 6 to a bridge-piece 4 forming an integral part of the said body is a pin 5. This pin carries and serves as a pivot for a holder 2 with handle 3. The outer end of the pin 5 terminates in a fork 7 designed to receive a pivoted handle

35 13, the upper portion thereof being adapted to engage the recess 8 of an extension of the holder 2 and in such position preventing a rotary movement of the body 1 in relation to the said holder. If therefore during the

40 use of the flatiron its lower part has been cooled off, the handle 13 is swung free of engagement with the recess 8 and thereafter caused to be turned about an angle of 180 degrees which movement causes a corresponding rotary movement of the pin 5.

45 The face of the iron formerly at the top is thus placed at the bottom in relation to the handle 3. Subsequent to this manipulation the handle 13 is made to re-engage the recess 8 thereby once more safeguarding

a turning movement of the body 1 relative to the holder. It will thus be seen that both the upper and lower faces of the flatiron may be used alternatively.

The electric current is obtained from any 55 convenient source and, by means of an electric wire 12, a contact member 10 and plugs 11, is conducted to the electric heating device in the following manner.

Each of the plugs 11 terminates in a 60 double nut 14 and each of these nuts is connected with a disk 18 by means of two wires 15 and clamps 19 suitably attached to the said disk, the wires 15 being mounted with-in grooves 15^a provided in the holder 2 in 65 the manner illustrated in Fig. 3. The disk 18 is slidably fitted on the holder part 2^a, the latter being so disposed that the grooves 15^a not only serve to house the aforesaid wires but also engage with projections 70 fashioned on the disk 18. In this way the disk, when the holder part 2^a is turned, is likewise turned.

Opposite the clamps 19 and secured to the bridge-piece 4 are contacts 20 each of which 75 is connected with the heating device 21 by means of a wire. In order to ensure a reliable contact between the clamps 19 and the contacts 20, the former are spring-con-trolled, a spring 16 and disk 17 of insulat- 80 ing material tending to press the clamps against the contacts 20.

Having now fully described my said in- 85 vention what I claim and desire to secure by Letters Patent is:—

In the herein-described electrically heated flatiron, the combination with a hollow iron body having an upper and a lower flat face and an integral and vertically disposed bridge-piece near its rear part, of an elec- 90 tric heating device fitted within the hollow body and between its bridge-piece and front part; a pin secured to the bridge-piece and projecting from the rear part of the iron body; a holder with handle pivotally 95 mounted on said pin and having an out-wardly projecting extension; means to permit of the turning of the holder and handle in relation to the iron and secure them at right angles to its upper and lower faces, 100

the said means comprising a second handle linked to the projecting end of the aforesaid pin and adapted to engage the extension on the holder; and electric wire connections and a contact making device fitted on, respectively in, the said hollow iron body, all as and for the purpose set forth.

In testimony whereof I have hereunto set my hand in the presence of two subscribing witnesses.

ERNST MUNTWYLER.
